UPHOLSTERY FABRIC

Alfred T. Wilde, North Bergen, N. J.

Application April 12, 1955, Serial No. 35,489

Term of patent 3½ years

(Cl. D92—1)

The figure on the drawing is a plan view of an upholstery fabric showing my new design. The dot and dash lines on the drawing outline a design unit, which unit is repeated in regular succession as indicated by the extensions beyond the unit boundaries.

I claim:

The ornamental design for an upholstery fabric, substantially as shown and described.
